UNITED STATES PATENT OFFICE

JOHN EDWARD THORNTON, OF WEST HAMPSTEAD, LONDON, ENGLAND, ASSIGNOR TO
JOHN OWDEN O'BRIEN, OF MANCHESTER, ENGLAND

MULTICOLOR CINEMATOGRAPH FILM MATERIAL

Application filed December 7, 1925, Serial No. 73,948, and in Great Britain December 19, 1924.

This invention relates to the manufacture of a special form of double width sensitized material for the production of multi-color positive cinematograph films.

5 According to the invention the film material comprises a transparent support equal in width to two picture areas, a sensitized panchromatic gelatino-silver bromid emulsion layer upon one side of the transparent support and a non-sensitized multi-color colloid layer arranged in two half widths upon the other side of the transparent support each half width comprising a mosaic pattern filter screen in two colors.

10 15 The invention will be described with reference to the accompanying drawings:—

Fig. 1 is a transverse section greatly enlarged in depth through a double width negative film material made according to the invention the picture being photographed through the color screen and celluloid base as shown by the arrow A.

20 Figs. 2, 3 and 4 are plan views greatly enlarged of portions of the four colored gelatine adjacent to the centre line of the double width strip.

Figs. 5, 6 and 7 are similar plan views of a double width strip having a three color color screen.

30 Fig. 8 is a plan view of the double width strip showing the coating of sensitive gelatino silver bromid panchromatic emulsion thereon.

The film base or support consists of a strip of transparent waterproof material such as celluloid, cellulose-acetate, or the like of double standard width (Fig. 8) and approximately rather less than half standard film base thickness.

40 This transparent support is coated upon both sides with an adhesive substratum of the usual kind to ensure perfect adherence thereto of the next layer.

Upon one side of the film, superimposed upon the substratum, is applied a layer of 45 gelatine or other suitable colloid, upon or in which is formed a pair of color-groups of lines or dots (Figs. 2-7) by printing or staining the gelatine with dyes of two mor- danted colors arranged in the form of two different pairs each containing two colors, the

colors of one pair being different from the colors of the other pair.

When this layer has been perfectly applied, finished, and dried, the opposite side of the support is coated with a layer of panchromatic gelatino-silver-bromid emulsion of the usual fine-grain type (Fig. 1).

The multi-color gelatine layer for four-color pictures consists of an immense number of exceedingly fine colored areas in the form of dots, lines, or mosaic pattern (Figs. 2-4) disposed in two groups (each of two colors) side-by-side upon the two halves of the double-width film strip. The dots, lines, or other form of fine colored areas are placed in close juxtaposition with their two colors intermixed, preferably in equal proportions of each, and one pair of colors is placed upon one strip and the other pair upon the other strip of the double-width, and the colors of each pair in the group are different.

55 The colors used for a four-color set are preferably crimson-red and blue-green for one half the film, and blue-violet and orange-yellow for the other half. These form one complete color-group. Each half of the double-width film therefore contains its own complementary color, and the two halves are also complementary to each other. This particular arrangement however is not necessarily a hard and fast rule, though it is preferred.

60 The multi-color gelatine layer for three-colors is of a similar character consisting of fine dots, lines, or mosaic pattern (Figs. 5-7) but the colors comprise only crimson-red, blue-green, and blue-violet, and are therefore only semi-complementary. They are arranged in two groups, one upon each half of the double-width film as in the preceding example, but one of the colors is duplicated upon each half in order to fill the fourth space. For example, one half-width may have a half-group of crimson-red and blue-green, and the other a half-group of blue-violet and blue-green.

65 70 75 80 85 90 95 100 In making pictures by means of this film-material negative-images in monochrome gradations (preferably black silver) are formed in one layer and multi-colored posi-

tive-images in the other layer, the negative-images being used only for the temporary purpose of printing and producing the permanent positive-images, after which the temporary negative-images are removed from the film or plate, leaving thereon only the pair of multi-color-mosaic transparent positives.

After these black-silver primary images have been printed, developed and finished as described in Serial No. 73,947 filed December 7, 1925, the second step consists in sensitizing the multi-color gelatine layer upon the other side of the film before the final multi-color images can be produced.

This sensitizing process is conveniently carried out in the film-printing factory where the prints are made and therefore forms no part of the actual film manufacture, but to make the entire processes of sensitizing quite clear this sensitizing process will now be described.

The best method of rendering the multi-colored gelatine layer sensitive to light is by treating it to a bath of one of the bichromate salts of the usual type and strength (applied to the multi-colored gelatine layer only) by means of coating rollers until the layer is completely saturated with the bichromate solution, after which the film is again dried.

What I claim as my invention and desire to protect by Letters Patent is:—

1. A double-width multi-color positive film material comprising a transparent support equal in width to two picture areas, a sensitized panchromatic gelatino-silver bromid emulsion layer upon one side of the transparent support and a non-sensitized multi-color colloid layer arranged in two half-widths upon the other side of the transparent support each half width comprising a mosaic pattern filter screen in two colors.

2. A double-width four color positive film material comprising a transparent support of double picture area, two different kinds of image layers thereon, one layer being ready sensitized and consisting of a panchromatic gelatino-silver-bromid emulsion, the other layer being non-sensitized and consisting of interspersed mosaic pattern of colored colloid, the two different kinds of layers being formed upon and attached to opposite sides of the transparent support the multi-colored layer being formed as two parallel stripes each of two colors the colors of one being different from the colors of the other.

3. An improved photographic film or plate material adapted to produce multi-color transparent positives in two parts, comprising in its construction:—(A) a double-area transparent support having a surface area equal to two picture-areas; (B) a double-area layer of temporary monochrome-image-producing gelatino-emulsion of silver-salts upon one side of the support; and (C) a double-

area layer of permanent multi-color-image-producing colloid, in the form of two colloid mosaics, one mosaic comprising two colors and the other mosaic comprising two other colors; the two differently-colored colloid mosaics being adapted to produce a complementary pair of half-pictures which when superimposed by cementing or combined by projection will produce a complete picture upon the other side of the support.

4. An improved photographic film or plate material for producing multi-color transparent positives in two parts as in claim 1, comprising layers adhered to their support and to each other by an interposed layer of adhesive substratum.

In testimony whereof I have hereunto set my hand.

JOHN EDWARD THORNTON.
